UNITED STATES PATENT OFFICE.

HOMER P. CHANDLER, OF MANSFIELD, OHIO, ASSIGNOR TO THE OHIO BRASS COMPANY,
OF MANSFIELD, OHIO, A CORPORATION OF NEW JERSEY.

CONDUCTOR SUPPORT.

Application filed August 19, 1924. Serial No. 732,922.

My invention relates to conductor supports and particularly for the supporting of trolley wires used in the operation of electric railways, and its main object is the connecting or supporting of the ends of two trolley wires in adjacent relation so as to constitute as near as possible, a continuous conductor.

My invention resides in the new and novel construction, combination and relation of the various parts hereinafter fully disclosed and set forth in the drawing accompanying this specification.

In the drawing:

Fig. 1 is a top plan view of my invention. Fig. 2 is a side view in elevation and partial section of my invention, showing two trolley wires in position, but before any strain is permitted, tending to separate the same.

Fig. 3 is a sectional view on the line 3—3 of Fig. 2.

Fig. 4 is a side view in elevation and partial section of my invention, showing the trolley conductors held thereby and under strain, tending to separate the same.

In the preferred embodiment of my invention, I employ a body member 1 provided with a tubular recess 2 extending through the body member in a longitudinal direction and adapted to receive the ends of a trolley wire, or other conductor 3 for the purpose of holding the same in a fixed and electrically connected relation. The body member is also provided with enlarged portions 4 which in turn are each provided with a recess 5 having side openings 6. These side openings may be upon opposite sides of each enlarged portion 4 or only on one side, as their function is to permit the placing or removal of the locking dogs 7, which are composed preferably of steel provided with teeth 8. Each recess 5 has an opening 9 into the tubular channel 2 whereby the locking dogs 7 may be brought into engagement with the ends of the conductors 3. In order to adjust the locking dogs relative to the trolley conductors 3 and to prevent their removal from the recess 5 only at will, I employ two adjusting nuts 10 having threaded engagement with the body member 1 whereby they may be moved toward or away from the conductors 3 and thereby move the locking dogs 7 toward the conductor or permit the removal

of the locking dogs away from the conductor. 55 In other words, the nuts 10 adjust the relation of the locking dogs 8 relative to the conductor 3. The body member is also provided with a web 11 at each end for stiffening and strengthening the same.

The ends of the adjusting nuts 10 which engage the dogs 7 are preferably rounding, so as to permit the dogs 7 to rock freely or pivot about the end of the adjusting nuts whereby the dogs 7 act as a cam or wedge 65 between the adjusting nuts 10 and the conductors 3 when there is a tendency for the conductors 3 to pull apart, as shown by the arrows in Fig. 4. It will be noted that the recesses 5 are provided with side walls 12 70 below the openings 6 which together with the end of the adjusting nuts 10 prevent the removal of the dogs 7.

To install my invention, the ends of the conductor 3 are forced into the tubular 75 channel 2 until the ends pass the dogs 7 and abut against each other as near the center of the body member as possible. In order to permit the positioning of the conductors 3, it is necessary that the adjusting nut 10 80 shall be raised sufficiently to permit the locking dogs 7 to rise and allow the conductors to pass the same. As soon as the conductors are positioned, the adjusting nuts are screwed down into engagement with the dogs 85 7, moving them into firm engagement with the ends of the conductor 3. This engagement can be varied according to the force exerted upon the adjusting nut 10. As soon as strain is brought upon the conductors 3, 90 tending to separate them, the teeth 8 of the dogs 7 will bite into the conductor 3 and the dogs 7 will be rotated or pivoted about the end of the adjusting nut 10 and tend to assume the position shown in Fig. 4. From 95 this, it will be noted that the greater the strain tending to separate the conductors 3, the greater will be the tendency for the dogs 7 to resist the separation of the conductors 3.

It is quite apparent that when the end of the dogs 7 engages the inner side walls of the recess 5, that any further movement of the conductors 3 away from each other must either force the wall 13 downward or shear the metal of the conductor. In other words, the engagement of the dogs 7 with the walls of the recess, as shown in Fig. 4, amounts 100 105

to a positive lock to the extent of the strength of the device or the resistance to shearing of the conductor 3.

There are, of course, many modifications which will suggest themselves to one skilled in the art and I do not wish to be limited otherwise than by my claims.

I claim:—

1. A conductor splicer comprising a body member and a longitudinal recess therein to receive the end of the conductor, a movable dog arranged to project into the recess and engage the conductor in such manner that the conductor may be positioned within the recess but not withdrawn and adjustable means about which the dog pivots for moving the dog towards the conductor.

2. A conductor splicer comprising a body member and a longitudinal conductor-receiving recess therein, a pair of movable dogs arranged to project into the recess and engage the surface of the ends of the conductor in such manner that the end of the conductors may be positioned within the recess in adjacent relation but not withdrawn and adjustable means about which the dogs pivot for moving the dogs towards the conductors and preventing them moving away from the conductors.

3. A conductor splicer comprising a body member and a longitudinal conductor-receiving recess therein, an enclosure, an opening thereto through the side of the body member and through which a dog may be positioned within or removed at will from the recess and an opening leading from the enclosure into the recess, a movable dog in the enclosure adapted to project into the recess and engage the conductor and permit the positioning of the conductor in the recess but prevent its being withdrawn.

4. A conductor splicer comprising a body member and a longitudinal conductor-receiving recess therein, an enclosure, a side opening thereto and an opening leading

from the enclosure into the recess, a longitudinally movable and removable dog in the enclosure adapted to project into the recess and engage the conductor and permit the positioning of the conductor in the recess but prevent its being withdrawn.

5. A conductor splicer comprising a body member and a longitudinal conductor-receiving recess therein, a pair of enclosures and access to each enclosure, an opening from each enclosure leading into the recess and a movable dog in each enclosure projecting into the recess to engage the surface of the conductor ends when positioned within the recess and arranged to prevent the conductors being withdrawn and means to move and maintain the dogs in engagement with the conductors and about which the dogs pivot.

6. A conductor splicer comprising a body member having a continuous longitudinal recess to receive the ends of conductors, a pair of enclosures and a dog in each enclosure free to move longitudinally away from each other a limited distance and projecting into the recess and arranged to grip the ends of the conductors and manually adjustable means to move the dogs towards the conductors and maintain the dogs in engagement with the conductors.

7. An article of manufacture for attachment to a conductor to grip and hold the same comprising a body member having a recess therein to receive the end of the conductor, a movable dog arranged to project into the recess and engage the conductor such that the conductor may be positioned within the recess and held against removal by the dog, adjustable means about which the dog pivots for moving the dog toward the conductor and means for attaching holding means to the body member to maintain a tension in the conductor.

In testimony whereof I affix my signature.

HOMER P. CHANDLER.
